HUMIDIFIER

Leroy W. Hoyt, Stamford, Conn.

Application February 7, 1935, Serial No. 5,363

7 Claims. (Cl. 261—119)

This invention relates to new and useful improvements in humidifiers and has for an object to provide a humidifier which may be easily and quickly applied to an existing heating system without the use of special tools and without the necessity of providing special connections.

Another object is to provide a humidifier particularly adapted for connection with a steam radiator or any steam line, and which operates entirely automatically with the heating cycles of the system and which is noiseless in its operation.

A further object is to provide a humidifier having the characteristics indicated and which functions to evaporate into the surrounding atmosphere water of condensation from the heating system to which it is applied, and which prevents the release into the surrounding atmosphere of steam from the heating system.

Other objects and advantages will become apparent from a consideration of the following detailed description taken in connection with accompanying drawing wherein a satisfactory embodiment of the invention is shown. However, it will be understood that the invention is not limited to the details disclosed but includes all such variations and modifications as fall within the spirit of the invention and the scope of the appended claims.

In the drawing:

Fig. 1 is a view partly in side elevation and partly in section showing the present humidifier connected with a radiator; and

Fig. 2 is a top plan view with parts broken away and showing the humidifier connected with a radiator.

Referring in detail to the drawing a portion of a steam radiator is generally indicated at 5 and the improved humidifier generally designated 6 is shown as connected with the end section 7 of the radiator through a nipple or bushing 8 adjacent the top of the radiator. This nipple is in the usual core opening in the upper part of the radiator section. The humidifier 6 comprises a cast body 9 cored out to form a steam or condensing chamber 10 in communication with the interior of the radiator through a connection or nipple 11 cast with the body 9 and screw threaded into the bushing or nipple 8 as shown. A screen or strainer 4 is preferably provided in this connection to prevent passage of scale from the radiator into the humidifier. Chamber 10 is bounded or defined by an inner wall 12 and an outer wall 13 and these walls are zig-zag or fluted to increase their surface areas and also to

provide upright air passages 14 at the outer surface of the wall 13.

The inner wall 12 together with an inner horizontal wall 15 forms a central water or evaporating chamber 16 in which is located a float 17. A bushing 18 is threaded through an opening in wall 15 and has its lower end shaped to provide a seat for a valve 19 the stem 20 of which extends through the bushing and into the evaporating chamber 16 wherein it is connected with the float 17. The valve stem 20 has its upper end headed or enlarged at 21 and loosely received in a small compartment or socket 22 formed at the lower side of the float 17. With this construction it will be appreciated that the float has a universal connection with the valve stem and so when the water in chamber 16 boils the float may move about relative to the valve stem 20 in all directions without unseating the valve. It will be seen that the valve stem passes through the strap 23 which is connected at its ends with the float, and that the head 21 on the valve stem prevents separation of the float and stem.

A cylinder 24 is formed with the bottom wall of the evaporating chamber concentric with the valve seat in the bushing 18 and extends downwardly to a point adjacent the bottom wall of the condensing chamber 10. Located within the cylinder 24 and secured to or integral with the lower side of the valve 19 is a piston 25 peripherally grooved as at 26 whereby a water seal is formed between the piston and cylinder. This piston is somewhat smaller than the cylinder to provide sufficient clearance for water to flow past the piston. Screw threaded into the lower end of the cylinder 24 is a member 27 having an opening 28 therethrough normally closed by a ball or non-return valve 29.

To the lower end of the body 9 there is removably secured a cover or closure 30 which is preferably concaved or somewhat hollow as shown. This closure may be secured in place as by screws 31 and is removable to permit of cleaning of the humidifier and when not in place gives access to the interior of the unit to facilitate assembly. Threaded through the member 30 is the stem 31 of a needle valve 32, and it will be apparent that by turning the handle 33 in one direction or the other the valve 32 will be advanced to seat in the opening 28 or will be retracted from such opening. Normally the valve 32 is only used to close the opening 28 when the humidifier is not to be used.

A cover 34 is secured over the upper end of the body 9 as by means of screws 35 and the cover is

held in spaced relation to the upper end of the body by means of spacer lugs 36. In its center portion above the upper end of the evaporating chamber the cover 34 is provided with an opening 37, and the cover is of such diameter as to extend entirely across the upper end of the body 9 and to overlie the upper ends of the flutes or upright passageways 14 in the outer wall 13 of the body. The outer edge portions 38 of the cover are 10 preferably downturned about the upper edge of the body as shown.

The cover 34 collects the air passing upwardly through the flutes 14 and directs such air inwardly over the top of the evaporating chamber 16 as suggested by the arrows in Fig. 1. The air is thus brought into contact with the vapors arising from the chamber 16 and picks up and mixes with the moisture and passes outwardly through the opening 37. As the moisture laden air passes 20 outwardly through the opening 37 it engages the underside of a baffle plate 39 disposed above said opening and supported as by the spaced posts 40. The baffle plate deflects the moistened air outwardly so as to scatter it and the effect of using this plate is that a rising stream or column of vapor is not visible above the humidifier. Further, the plate 39 serves to keep dust from settling in the chamber 16.

In the operation of the humidifier steam entering the chamber 10 engages the walls 12 and 13 and heating them is cooled and condensed and flows down the walls to the lower part of the chamber 10. The outer walls 13 of the chamber 10 are cooled by an upward flow of air over their outer surfaces and through the passages or flutes 14 thereby expediting the condensing of the steam in the chamber 10. Any air in the chamber when the steam first enters it is vented into the radiator through the lower part of the nipple 11, while 40 the steam enters the chamber through the upper part of the nipple, the latter being made large for this purpose.

The water collected in the chamber 10 is forced around the piston 25 into the cylinder 24 by the 45 steam pressure in the upper portion of the chamber from the radiator. When the water in chamber 16 reaches a predetermined level about as shown in Fig. 1 the float 17 is raised sufficiently to cause the valve 19 to seat and thus cut off communication between the chambers 10 and 16. As the water is evaporated from the chamber 16 the float 17 will drop to bring about opening of the valve 19 so that additional water may be forced from the chamber 10 into the chamber 16.

55 Piston 25 insures closing of the valve 19 and prevents leakage of water by the valve since the water as it is forced into the cylinder carries the piston upwardly to assist the float in closing the valve, the water leaking by the piston when the valve is being held closed by the float and equalizes the pressure at each side of the piston. When this has occurred (if the water level in the chamber 16 is sufficiently low) the weight of the float 60 on the stem 20 will cause unseating of the valve so that additional water may enter the evaporating chamber. From this it will be understood that the valve 19 has movement upwardly and downwardly until the water reaches the proper level in the chamber 16.

70 Non-return valve 29 serves to prevent water passing from the chamber 16 back to the chamber 10 when the steam pressure drops and there is a partial vacuum in the heating system. This non-return valve is easily unseated by the steam pres-

sure when water is to be forced into the cylinder 24 and from the cylinder into the evaporating chamber 16. When it is desired that the humidifier cease to function it is but necessary to operate the hand piece 33 until the valve 32 is tightly seated, closing off the opening 28.

Attention is also directed to the fact that the outlet through the connection 11 is located a substantial distance above the bottom of the condensing chamber. With this arrangement the water from such chamber will not overflow back into the radiator until there is a substantial volume of water in the lower portion of the condensing chamber and then water may flow to the radiator through the lower portion of connection 11 while steam moves through the upper portion of said connection into the chamber 10. Further, the humidifier does not discharge steam directly from the radiator and the steam portion of the chamber 10 being sealed there is no noise 20 of escaping steam.

Since the outer wall 13 of the condensing chamber is zig-zag or fluted this wall has a very large radiating area against which air moves to be heated and so the steam entering the chamber 10 is rapidly condensed. As the wall 12 is also zig-zag or fluted such wall has a great deal of surface area to take up the heat from the steam in chamber 10 and to transmit such heat to the water in the evaporating chamber 16. It will be appreciated that as the wall 12 takes heat from the steam in the chamber 10 condensing of the steam is further facilitated. Water is also drawn up on the inner surfaces of the walls 12 where it is evaporated by the heat. With the cylinder 24 extending to the lower end of the chamber 10 it will be apparent that water for the evaporating chamber 16 is taken from the lower end of the condensing chamber and that water will not remain in the lower end portion of the latter and become cold.

From the foregoing description it will be apparent that the present humidifier may be connected with any steam line where humidity is required and will operate in accordance with the heating cycles of a system to which it is connected. That is, each time the steam pressure comes on the water in the evaporating chamber 16 will be heated and if such chamber is not filled to the desired level additional water will be forced into it. The device is entirely automatic in its operation and is noiseless, and there is no visible cloud of moisture discharged about it. It operates by condensing steam from the radiator or other steam line and then evaporating the water of condensation. It is not necessary that air from the heating system be vented into a room through the humidifier but is discharged back to the system and air from the room is prevented from entering the heating system through the humidifier.

Having thus set forth the nature of my invention, what I claim is:

1. In a humidifier, a body comprising a condensing chamber adapted for connection with a steam line, an evaporating chamber within and heated from the condensing chamber and open at its upper side, a connection between the chambers whereby water of condensation from the condensing chamber is fed to the evaporating chamber, means controlling such feeding of water of condensation, a cover over and spaced from the upper ends of the condensing and evaporating chambers and having an opening over the upper open side of the evaporating chamber, and

the outer wall of said condensing chamber being fluted to provide upright air passages over the upper ends of which said cover extends to direct inwardly over the upper open side of the evaporating chamber the air passing upwardly through said flutes.

5. In a humidifier, a body including inner and outer walls forming a condensing chamber between them and of which the inner wall defines an evaporating chamber heated from the condensing chamber and open at its upper side, means for connecting said condensing chamber with a steam line, a connection between the chambers whereby water of condensation from the condensing chamber is fed to the evaporating chamber, means controlling such feeding of water of condensation, and each of said inner and outer walls fluted with the flutes of said outer wall extending vertically whereby the outer wall has a large surface area exposed to the atmosphere to facilitate the condensing of steam in the condensing chamber and for the heating of air adjacent the humidifier and whereby the inner wall has a larger surface area for the transmission of heat from the steam of the condensing chamber to the water in the evaporating chamber.

6. In a humidifier, a condensing chamber, means for connecting the chamber with a steam line and adapted to collect water of condensation in its lower portion, an evaporating chamber within said condensing chamber and open at its upper side and having an opening in a wall, a cylinder communicating said opening with the lower portion of the condensing chamber, a valve controlling the passage of water through said opening, a float within the evaporating chamber and connected with said valve to cause seating thereof on the water in the evaporating chamber reaching a predetermined high level, and a piston in said cylinder and connected with said valve and operable by the pressure of water entering the cylinder from the condensing chamber to assist the float in moving the valve to seated position.

7. In a humidifier, a condensing chamber for connection with a steam line and adapted to collect water of condensation in its lower portion, an evaporating chamber within said condensing chamber and having an opening in its bottom wall, a cylinder communicating said opening with the lower portion of the condensing chamber, a valve controlling the passage of water through said opening from the condensing to the evaporating chamber, a float within the evaporating chamber and connected with said valve to cause seating thereof on the water in the evaporating chamber reaching a predetermined high level,

and a non-return valve in said cylinder and preventing movement of water from the cylinder into the condensing chamber.

5. In a humidifier, a condensing chamber for connection with a steam line and adapted to collect water of condensation in its lower portion, an evaporating chamber within said condensing chamber and having an opening through one wall, a cylinder communicating said opening with the lower portion of the condensing chamber, a valve controlling the passage of water through said opening, a float within the evaporating chamber and connected with said valve to cause seating thereof on the water in the evaporating chamber reaching a predetermined high level, a piston in said cylinder and connected with said valve and operable by the pressure of water entering the cylinder from the condensing chamber to assist the float in moving the valve to seated position, and non-return valve in the lower portion of said cylinder and preventing movement of water from the cylinder into the condensing chamber.

6. In a humidifier, a body comprising a condensing chamber adapted for connection with a steam line, an evaporating chamber within and heated from the condensing chamber and open at its upper side, a connection between the chambers whereby water of condensation from the condensing chamber is fed to the evaporating chamber, means controlling such feeding of the water, the outer wall of said condensing chamber fluted to provide upright air passages, a cover over and spaced from the upper ends of the condensing and evaporating chambers and having an opening over the open upper side of the evaporating chamber, said cover extending over the upper ends of said air passages to collect and direct inwardly over the upper open side of the evaporating chamber the air passing upwardly through said passages, and a baffle plate supported in spaced relation to said cover and disposed over the opening therein.

7. In a humidifier, a condensing chamber, means for connecting it with a steam line, an evaporating chamber heated from said condensing chamber, a connection between said chambers whereby water from the condensing chamber will be fed to the evaporating chamber, means controlling such feeding of water, means in said connection and having an opening therethrough, a non-return valve adapted to close said opening and prevent the movement of water from the evaporating to the condensing chamber, and a manually operable valve also operable to close said opening to render the humidifier inoperative.
